UNITED STATES PATENT OFFICE.

JOHN DEMAINE, OF GREYSTONE, RHODE ISLAND.

WEFT-THREAD CUTTER FOR AUTOMATIC LOOMS.

Application filed January 15, 1928. Serial No. 81,405.

This invention relates to thread-severing mechanism for automatic looms; and has for its object to provide in such a loom a cutter to be operated by action of the loom 5 for severing the trailing thread of the spent bobbin each time a change of the bobbin is effected.

A further object of the invention is to mount a cutter on the replenishing side 10 of the loom and to provide means whereby the replenishing mechanism will move the cutter to open position and the action of the lay will close the cutter to sever the thread.

A still further object of the invention is 15 to provide means in the cutter for clamping and holding the severed end of the thread leading from the selvage to prevent this thread from being carried back into the weft by further action of the shuttle.

With these and other objects in view, the 20 invention consists of certain novel features of construction, as will be more fully described, and particularly pointed out in the appended claims.

In the accompanying drawings:

Figure 1 is a top view illustrating the position of the cutter at the replenishing end of the loom and as mounted on the breast beam.

Figure 2 is a diagrammatic view illustrating a portion of the weft replenishing mechanism controlled in its action by the feeler mechanism to effect the opening of the cutter previous to transferring the bobbin from 35 the shuttle.

Figure 3 is a side elevation partly in section illustrating my improved cutter with the movable blade closed by a forward movement of the lay.

Figure 4 is a top edge view of the cutter.

Figure 5 is a side elevation illustrating the movable cutter blade in open position and the presser finger as extended into position to be engaged by the last end of the forward movement of the lay.

Figure 6 is a front edge view of the cutter blades in section illustrating the clamping action of the movable blade on the thread during the closing movement thereof.

Figure 7 is a perspective view showing the outer end of the cutter supporting arm with its extremity bent at a right angle thereto and provided with a guide opening.

Figure 8 is a perspective view showing a portion of the fixed cutter blade removed.

Figure 9 is a sectional view of the under side of the arm supporting box sectioned on line 9—9 of Figure 10, showing a portion of the arm and the spring therein.

Figure 10 is a sectional elevation on line 10—10 of Figure 9.

It is found in the practical operation of automatic looms particularly the drop box type for weaving different colors, of advantage to provide a cutter which is located close to the selvage so as to cut the spent weft just previously to the transfer of the bobbin and to so shape the cutter device as to clamp and hold the severed thread between the shuttle box and the selvage to prevent the end from being drawn back into the cloth by further action of the shuttle, the cutters being so shaped that they will discharge the thread held between them upon the next opening action of the movable blade. Further, it is found of advantage to positively open the movable blade of the cutter by action of the replenishing mechanism and to positively move the blade to closed position by action of the lay as it approaches the last end of its forward stroke; and the following is a detailed description of the present embodiment of my invention and showing one construction and arrangement of weft severing mechanism by which these advantageous results may be accomplished:

With reference to the drawings, 10 designates the breast beam of a loom on which my improved weft severing mechanism 11 is operatively mounted. This mechanism comprises essentially a relatively long supporting arm 12, the forward end of which is mounted to slide endwise in the openings 13 and 14 of the box-shaped bearing member 15. This bearing box is preferably formed with slots 16 through which fastening bolts 17 are passed so that it can be adjusted forward and back to nicely regulate the positions of the cutter relative to the action of the lay 18. This box is provided with a web 19 which extends a portion of its length leaving a space 20 at one end thereof whereby the spring abutment pin 21 may be passed through a hole in the arm against which one end 22 of the spring rests, the opposite end 23 of the spring engaging the outer end or wall of the box whereby the cutting mechanism is yieldingly supported in operating position so that if a shuttle should stop on the lay directly in front of the cutter the

whole cutter mechanism would yield and be pressed forwardly by the lay without a smash occurring.

On the free end 24 of this arm, I have formed a laterally-extending end portion 25 slotted as at 26 for the purpose, presently described. Mounted on the pivot pin 27 on this arm is the movable cutter blade 28, the same having a cooperating shearing edge 29 and this blade is provided with an upwardly-extending shoulder portion 30 which has formed therein a circular recess 31 for the reception of the head 32 of the presser finger 33, the free end of this finger being guided through this slot 26 in the offset portion 25 of the arm 12 and this movable blade is provided with a forwardly-projecting operating handle 34.

Cooperating with this movable blade is the fixed blade 35 which is provided with a hole 36 through which the pivot pin 27 also passes, a nut 62 thereon serving to bind this blade in set position. This blade is provided with a shearing edge 37 which cooperates with the edge 29 of the movable blade to shear the thread and this fixed blade is also provided with a rearwardly-extending bearing portion 38 which also extends into the opening 26 in the offset 25 of the arm 12.

In order to adjust the shearing action of this fixed blade to properly cooperate with the movable blade, I have provided an adjusting screw 39 which is threaded through the arm 12 with its inner end resting against the inner surface of this blade 35 at its lower edge 40, see Figure 3, whereby the inward adjusting of this screw 39 serves to tip the blade on its pivot pin 27 to cause a closer shearing action of the cooperating shearing edges 29 and 37.

During a regular weaving action of the loom the movable blade is held in closed position and in order to open this blade at the proper time, I have connected its operating handle 34, as shown diagrammatically in Figure 2, to the arm 41 of the weft replenishing mechanism by the connecting rod 42 and the extension lever arm 43, whereby when the usual feeler mechanism 44 finds an exhausted bobbin in the shuttle 45, the abutment pin 46 is caused to remain beneath the lever 47, whereby upon the next downward movement of this lever, through action of cam 48 and connecting rod 49, this lever engages this abutment 46 and through the connector 50 tips the free end of lever 51, which is pivoted on shaft 52, upwardly thus carrying the latch bar 53 upwardly until the latch 54 engages the arm 41, whereupon the next upward movement of the cam 48 acts upon the lever 47 through the rod 49, to cause this lever to engage the fixed abutment 63 and so through the connection 50 causes the free end of arm 51 to move the latch bar 53 downwardly and so swing the arm 43 upwardly to its dotted position shown in

Figure 2, which swinging movement opens the cutter to receive the weft thread which is passed thereinto as the shuttle is thrown across the lay. The effective downward movement of this latch bar upon the arm 43 is limited by its end 60 coming in contact with the bar 61 which trips it.

The mechanism operated by this latch bar 53 is restored by action of levers 57 and 58 and connection 59 through the usual mechanism, not shown.

As the lay now comes on its beating-up stroke, the upwardly-extending portion 55 thereof engages this forwardly extending presser arm 33 of the cutter, which is at that time in position illustrated in Figure 5, driving the same back and causing the thread 56 to be first clamped between the movable cutter blade 28 and the inner surface of the supporting arm 12, as best illustrated in Figure 6, the thread being finally severed when the shearing edge 29 of this blade cooperates with the shearing edge 37 of the fixed blade. The movable blade then remains closed thus retaining the end of the severed thread 56 until the cutter opening operation above described is repeated.

It will be noted that the cutter carrying arm 12 is provided with an abutment end portion or shoulder 64 against which the thread 56 may engage in being drawn into the cutter which abutment serves to limit the distance the thread shall be drawn into the cutter. By this construction the thread is prevented from jamming, clogging, or choking the cutter as the further the thread is gripped from the pivot point the more effectually it is acted upon by the opening action of the cutter blade to withdraw the thread from its clamped position and so clear the cutter, which clearing action is not affected where the thread is drawn in close to the pivoting point.

My improved weft thread supporting device is extremely simple and practical in construction, is positive in its operation and both its opening and closing actions are positively effected by action of the loom; also by the construction of my improved cutter the weft thread is securely clamped by the cutter blade and is retained in that clamped position until this cutter blade is again opened at which time this thread is released and will by the opening movement of the blade drop out and free the cutter.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a weft thread replenishing loom having in combination, a lay, a weft replen-

ishing mechanism, a weft thread cutter device comprising an upper fixed cutter plate, a clamp plate spaced from the cutter plate, a cooperating movable lower blade mounted between said plates, and an endwise slidable presser finger pivotally connected to said lower blade at a point between said plates and retained in attachment with said cutter by said plates, the free end of said finger extending into the path of movement of the lay to be engaged thereby to operate said blade and sever the thread.

2. In a weft replenishing loom having in combination a lay, a weft replenishing mechanism, a cutter supporting arm mounted on the loom frame, a fixed cutter plate, a thread clamp plate spaced from the cutter plate, a cutter having a movable blade pivoted to said arm between said plates, an endwise slidable cutter closure member guided in said arm and pivotally connected to said movable blade to extend into the path of movement of the lay to be engaged by its forward swinging to close said blade and sever the thread, the pivoted end of said

closure member being retained in attached position to said movable cutter by the fixed cutter on one side and the clamp plate on the other side.

3. In a weft replenishing loom having in combination, a lay, a weft replenishing mechanism, a cutter device having one fixed cutter plate, a thread clamp plate spaced from the cutter plate, a cutter blade pivoted between said plates with its shearing edge extending rearwardly from the pivot and a shoulder portion extending upwardly from the pivot between said plates, a closure member slidably guided in said arm and pivotally connected by a ball and socket joint to the shoulder portion of said movable blade between said spaced plates and arranged to extend into the path of movement of the lay to be engaged by its forward swing to close said blade and first bind the thread between it and said arm and subsequently sever the thread.

In testimony whereof I affix my signature.

JOHN DEMAINE.
